PROCESS AND DEVICE FOR FULL-CELL TREATMENT OF TIMBER AND SIMILAR MATERIAL

Bror Olof Häger and Stig Bertilsson Kjellström,
Stockholm, Sweden, assignors to Bolidens Gravaktiebolag, Stockholm, Sweden, a joint-stock company of Sweden.Application February 20, 1943, Serial No. 476,592.
In Sweden February 7, 1942.

11. Claims. (Cl. 21—65)

1. The impregnation of timber and similar material is effected in practice mainly in accordance with the empty-cell or the full-cell process. The empty-cell process is adopted when the preservative is an oil, the full-cell process when the preservative is dissolved or emulsified in some cheap liquid such as for instance water.

In principle, the empty-cell process proceeds in the following manner. The material to be treated is first exposed in an impregnating cylinder to an initial air pressure above the atmospheric pressure after which the cylinder is filled with the preservative oil, while the same pressure is maintained. The pressure in the cylinder is then increased, whereby the preservative oil is introduced into the material. After some time the cylinder is emptied of the preservative oil and the material is subjected to a vacuum, whereby part of the preservative oil is expelled from the cell-cavities of the material by the internal air pressure which prevails there. The consumption of the preservative oil is thus considerably reduced, as the cell cavities will be only partially filled with the preservative oil, whilst a uniform distribution of the preservative oil in the material is nevertheless obtained. When treating timber with preservative oils it is necessary to use the empty-cell process for economic reasons.

By full-cell process the material to be treated is subjected in a cylinder to a vacuum, after which the cylinder, while the vacuum is maintained, is filled with a solution or an emulsion of the preservative. The solution or emulsion is then introduced into the material by pressure, so that the cell-cavities are filled with solution or emulsion. When treating with solutions or emulsions the amount of preservative absorbed by the material is controlled by regulating the concentration of the solution or emulsion, so that the comparatively complicated empty-cell treatment need not be resorted to.

The present invention relates to a process and device for effecting full-cell treatment of timber and similar material. A device in accordance with this invention consists of a container for the solution or emulsion of preservative, a chamber or a cylinder in which the treatment takes place, a smaller container designed for vacuum and pressure and an air pump or air pumps for effecting vacuum and pressure, as well as piping for the connection of the different parts of the device and the requisite valves. A process according to the invention for effecting full-cell treatment of timber with a preservative solution or emulsion includes the feature of subjecting to

2. vacuum a charge of timber disposed in a treating zone communicating with a smaller zone; introducing preservative from a supply zone into said treating zone and said smaller zone with the aid of the vacuum until the charge of timber is substantially completely immersed in preservative and also the smaller zone is filled with preservative and, after closing the communication between the treating zone and supply zone, discontinuing the vacuum and applying superatmospheric pressure to the preservative in the smaller zone thus causing the cells of the timber in said treating zone to absorb preservative, this absorbed preservative being supplied from the smaller zone so that the timber in the treating zone remains completely immersed in the preservative throughout the entire treatment; opening the communication between the treating zone and the supply zone for removing from said smaller zone and from the treating zone the preservative not absorbed by the timber and removing the impregnated charge of timber from the treating zone.

An example of a device in accordance with this invention is shown in Figures 1 and 2 of the accompanying drawing. The device is used in the following manner. The impregnating chamber or cylinder A is filled with the material to be treated and is then closed, whereupon the air pump B creates a partial vacuum in the smaller container C and in the cylinder A, while the valve D is closed. After the partial vacuum has been maintained for the required time, the valve D is opened and solution or emulsion from container E is sucked into A and C, while the vacuum is maintained. When the level indicator F shows that the container C has been filled with solution or emulsion, the valve D is closed. An automatic valve G prevents the solution or emulsion from entering the pump B, thus acting as a safety device. The pump B is then caused to produce pressure, whereupon the material to be treated rapidly absorbs the solution or emulsion. The container C must be large enough to hold the maximum amount of solution or emulsion which the material can absorb. This container may also take the form of a dome on the cylinder A, this modification being shown more fully in Figure 2. When the material has absorbed the requisite quantity of the solution or emulsion, the valve D is reopened and, by the expansion of the compressed air produced in the container C during the pressure stage of the impregnating process, the solution or emulsion not absorbed or held within the cells or interstices of the material being treated is driven back to the container E, whereupon the valve D is closed. If

needed supplementary compressed air may be delivered during this period by the pump B. After this treatment the material if desired may for a short time be subjected to a vacuum. In this way small amounts of the solution or emulsion are sucked out from the outer layers of the material, which reduces the dripping from the material of the solution or emulsion after treatment. The material, when completely impregnated, is removed from the cylinder and is allowed to dry.

Impregnating in the device shown in the drawing may also proceed in the following manner. The cylinder A is filled with the material to be treated and is then closed, whereupon the pump B creates a vacuum in the container C and in the cylinder A, while the valve D is open. In this way solution or emulsion from the container E is sucked into the cylinder A. When the cylinder A has been entirely or partially filled with the solution or emulsion the valve D is closed. The pump B continues for some time to create a vacuum, after which the valve D is reopened. When the level indicator F shows that the container C has been filled with the solution or emulsion, the valve D is closed. The pump B is then caused to produce pressure, whereupon the treating process is continued in the same way as previously described.

An impregnating plant in accordance with the present invention can of course be provided with usual arrangements for drying, steaming and so on, of the material to be treated as well as for heating of the solution or emulsion. The container E may also be placed at a lower level than the rest of the plant, which will facilitate the driving back of the solution or emulsion from the cylinder A to the container E.

Owing to the simplicity of the apparatus, the management of an impregnating plant according to the present invention will be very easy. The initial and operating costs will also be low. Moreover, the course of the treatment can be well controlled as the amount of solution or emulsion absorbed by the material can easily be followed on the level indicator F.

An impregnating plant according to the present invention may be adopted for treatment of timbers and similar material with preservative solutions or emulsions containing an arsenic compound or arsenic compounds (such as preservatives according to the U. S. Patent No. 2,139,747).

Having thus described our invention, we declare that what we claim is:

1. A device for the full-cell treatment of timber comprising an impregnating chamber, a vented container for liquid preservative, means establishing communication between the lower portions of said chamber and container, a supplemental container having its bottom in communication with the top of said impregnating chamber, and pump means connected to said supplemental container at a point above the bottom thereof for creating vacuum or pressure.

2. A device as claimed in claim 1, characterized by the feature that said supplemental container is capable of holding at least the maximum amount of solution or emulsion of preservative which a normal charge of the material undergoing full-cell treatment can absorb.

3. A device as claimed in claim 1, in which the supplemental container takes the form of a dome on the impregnating chamber in which the full-cell treatment takes place.

4. A process for effecting full-cell treatment

of timber by means of a preservative which comprises subjecting to vacuum a charge of timber disposed in a treating zone, introducing preservative from a supply zone into said treating zone with the aid of the vacuum until the charge of timber is substantially completely immersed in preservative, continuing the application of vacuum to the timber in said treating zone while causing a smaller zone communicating with said treating zone to become substantially filled with preservative from said supply zone, discontinuing the vacuum and applying superatmospheric pressure to the charge of timber to cause the cells of the latter to absorb preservative, removing from the treating zone excess preservative not absorbed by the timber, and removing the impregnated charge of timber from the treating zone.

5. A process as in claim 4, wherein the charge of timber after impregnation with the preservative is subjected to a short vacuum treatment prior to its removal from the treating zone.

6. A process as in claim 4, wherein the said smaller zone is of a capacity sufficient to hold at least the maximum quantity of preservative that the charge of timber can absorb.

7. A process as in claim 4, wherein the preservative contains an arsenic compound.

8. A process for effecting full-cell treatment of timber by means of a preservative, which comprises subjecting to vacuum a charge of timber disposed in a treating zone communicating with a smaller zone; introducing preservative from a supply zone into said treating zone and said smaller zone with the aid of the vacuum until the charge of timber is substantially completely immersed in preservative and also the smaller zone is filled with preservative and, after closing the communication between the treating zone and supply zone, discontinuing the vacuum and applying super atmospheric pressure to the preservative in the smaller zone thus causing the cells of the timber in said treating zone to absorb preservative, this absorbed preservative being supplied from the smaller zone so that the timber in the treating zone remains completely immersed in the preservative throughout the entire treatment; opening the communication between the treating zone and the supply zone for removing from said smaller zone and from the treating zone the preservative not absorbed by the timber and removing the impregnated charge of timber from the treating zone.

9. A process as in claim 8, wherein the charge of timber after impregnation with the preservative is subjected to a short vacuum treatment prior to its removal from the treating zone.

10. A process as in claim 8, wherein the said smaller zone is of a capacity sufficient to hold at least the maximum quantity of preservative that the charge of timber can absorb.

11. A process as in claim 8, wherein the preservative contains an arsenic compound.
